SERGIO J VASSALLO Y VALLADARES, OF HABANA, CUBA.

SYSTEM OF SIGNALS.

Application filed April 1, 1924, Serial No. 703,502, and in Cuba March 4, 1924.

This invention refers to a system of signals applied especially at railroad crossings; crossing with other railroad lines or on level roads in highways, streets, etc., and its principal object is to provide a system of signals which is operated upon the passing of a train or other rolling load, prior to its arrival at the danger zone; and maintained in operation until the train or rolling load has passed the danger point.

One of the objects of this invention is to provide means by which a visible signal during the day and a luminous signal during the night may be displayed, and a sounding signal may be heard which signals may be operated simultaneously and independently one of another.

A further object of this invention is to provide means by which the system can be applied not only to a single track line but also to multiple track lines using only one source of power and simple means to establish electric circuits.

A further object of this invention is to provide a system of signals the purpose of which is not only to protect railroad crossings but also danger zones in streets, highways, etc.

Another object of this invention is to provide in connection with this system a circuit breaking device adapted to be installed in connection with the track and operated by the weight of the passing rolling load.

Other advantages and purposes of the invention will appear in the course of development of this specification wherein reference is made to the accompanying drawings:

Figure 1—is a diagrammatical view of a typical installation of the system in a double track crossing.

Figure 2—shows diagrammatically on an enlarged scale an installation of the elements which form the system in connection with a double track.

Figure 3 shows a view similar to Fig. 2, the parts being in working position.

Figure 4—is a side elevation of a tower or column in which are arranged the means of operating the system as illustrated in Figures 2 and 3.

Figure 5—is a diagrammatical view partly in section which shows the component parts of the system which are enclosed in said tower or column.

Figure 6—is a side elevation in detail of

a track equipped with my novel circuit breaking device.

Figure 7—is a top view of the same.

Figure 8—is a vertical longitudinal sectional view on an enlarged scale taken along 60 the line 8—8 of Figure 7.

Figure 9—is a vertical transverse sectional view on an enlarged scale taken on line 9—9 of Figure 7.

Figures 10 and 11 are views in perspective 65 which show in detail parts of said circuit breaking device.

Figure 12—is a side elevation in detail of a modified form of the circuit breaking device, in connection with a track.

Figure 13 is a top view of same.

Figure 14 is a sectional vertical longitudinal view on an enlarged scale taken on line 14—14 of Figure 13.

Figure 15 is a sectional transverse vertical 75 view on an enlarged scale taken on line 15—15 of Figure 13.

Figure 16 is a perspective view in detail of a mechanism to operate several signals to be visible during the day.

This system substantially is constituted as follows:

A source of electricity, a set of signals which include a signal light, a signal to be visible during the day and a sounding signal; a relay to establish a circuit to operate said signals; a relay in circuit with the above relay causing the signals to cease and a plurality of circuit breaking elements arranged in the track and connected with the negative 80 pole of the source of electricity.

Assuming, as is shown in Figure 1 a crossing of a double track A and B, going and coming, several of the essential elements of the system, also the signals, as is shown 95 in Figure 1 can be enclosed in a tower or column 1 of suitable structure erected near the track. Therefore, enclosed in said tower is arranged a source of electricity 2, which may be a generator, battery, etc., and also 100 two relays 3 and 4 enclosed in a casing provided with suitable binding posts. Relay 3 is to operate the working of the signals and has two magnets 5 and 6 which are excited independently, instead of being arranged in 105 series as is usually done in this type of apparatus; this is due to the fact that the magnet 5 is arranged in a circuit of variable range which is always greater than that of magnet 6 and therefore it is essential that 110

magnet 6 must be especially constructed. Relay 3 has also an armature contact 7 between contact points 8 and 9 but which is forced into contact with the latter point by 5 a spring 10.

Relay 4 is of usual construction being used to break the circuit producing the drop of the signals. It has a magnet 11, as shown but in practice may have more than one 10 magnet. The armature contact 12 of this relay 4 is placed between contact points 13 and 14 being forced against the latter by a spring 15.

In connection with the rails of the tracks 15 A and B are arranged four circuit breakers 16, 17, 18 and 19 to be operated upon passing of a train.

The construction of these circuit breakers 20 will be explained later.

Finally in the diagrammatical views 2 and 3 and designated by the numerals 20, 21 and 22 respectively, are the lighting signal, the signal to be visible during the day and the sounding signal which is operated as will 25 be explained later.

Relay 3 has the following connections, a conductor 24 connecting the positive pole of the source 2 with magnet 5 and another conductor 24 connecting same with the circuit breaker 16 in the track, and a tapped wire 24' connected with the circuit breaker 19, a short connection between the magnet 6 and contact point 8; and three conductors 25, 26 and 27 connecting the contact point 8 30 with the signals 20, 21 and 22.

Relay 4 is connected by a line 29 to the positive pole of source 2 and to the armature contact 12. To the line 29 is connected a tapped line 30 which passes through the 40 winding of the magnet 11 and is connected with a branch line 31 which connects the track circuit breakers 17 and 18. A conductor line 32 connects the contact points 14 with armature contact 7.

The negative pole of source 2 has connected thereto a conductor line 32' which connects with a branch line 33. A conductor line 33' passing across the winding of the magnet 6, is connected to the contact point 50 8. Finally the lines 34—35 and 36 connect said negative pole with the signals 20, 21 and 22.

The circuit breakers 16, 17, 18 and 19 are to be constructed in a suitable manner for 55 the purpose of carrying the current, using the rail as a connecting element in establishing the circuits on passing of the train. A special construction of circuit breaker is shown in Figs. 6, 7, 8, 9, 10 and 11.

Referring to these figures numeral 37 60 designates the outer rail of track A, which rests on crosstie 38, it being assumed that rail 37 is cut, and that an attachment as detailed in Figure 11 is placed in the space enclosed 65 between the ends of the rail cut; this at-

tachment is formed by a support plate 40 and rail heads 41 spaced as is shown in 42, both heads being in alignment and nearly on a level with the cut ends of rail 37; projecting normally in space 42 of the plate 40 70 there are two space pins 43, and a longer intermediate pin 44, ending in a contact point 44' made of platinum tungsten or another nonoxidizing conductive material. The rail heads 41 and the plate 40 have bores 40' and 41' to assure its secure attachment to the track and to the rail heads. 75

In the space 42 is placed in a metallic parallelopiped casing 45 made of a single piece and shown in detail in Fig. 10. This casing is opened at both ends, having a sealed and water-proof inner center compartment 46 defined by partition 47. The casing at its bottom has at each end a longitudinal slot 45' extending up to each partition 47, and also an opening around which in the compartment 46 is formed a bell-shaped threaded hood 48'. The upper side of the casing 45 has both ends slightly bent downward, and on the lower side of these ends the pins 49 projects downwardly. 85

The compartment 46 has a lateral opening with an hermetical cover 50 made of insulating material. Casing 45 is set with the pins 43 and 44 passing through the slot 45' and through the opening 48 extending into the hood 48' pins 43 being in vertical alignment with the pin 49. The casing 45 is secured to the plate 40 by angular braces 51. Around pins 43 and 49 are placed spiral 90 springs 52 secured in place by plates 53 which are next to the pins; these springs are of a sufficient strength to yield only under pressure of a given weight.

To the hood 48' is attached a stuffing box 105 54 and the projecting end of pin 44 is threaded to receive a nut and counternut 54' for the purpose of preventing the casing from being pushed up by the strength of 110 springs 52.

On the inner face of the cover 50 is fastened a metallic bracket 55 which holds a pin 56 ending in a contact point 56' which pin is secured upwardly by a nut and lock nut 57, said pin has in its lower part a collar 58 and between this collar and bracket 55 is mounted a spiral spring 59 which permits the pin 56 to yield upon shock, said pin is in vertical alignment with the contact point 44' and connected therewith is a conductor of the system which passes through an opening in the cover 50. 115

In Figures 12 to 15 inclusive is shown a modified construction of circuit-breaker 120 to be used in certain cases, for instance when the system is to operate only with a given rolling-load. This circuit-breaker has the advantage that it is not necessary to make a change in the construction of the track, but, it is only to be used in the case where 125 130

the track is provided with an additional wheel or where there is a special construction in the rolling-stock.

This circuit-breaker consists of a plate 60, 5 which is fastened over the cross-ties of rail 37 together with the lower flange therewith and which plate has two spaced pins 61 and a third intermediate pin 62 ending in a contact point 62' made of tungsten, platinum 10 or another conductor of non-oxidizing material.

In connection with this plate there is an 15 hermetically sealed waterproof casing 63 which presents both ends extended forming a flange slightly bent downward 63' from the lower sides of which flanges projects downwardly a bushing 64.

The casing 63 has in the bottom an opening around which inside of the casing is 20 formed a bell-shaped threaded hub 65. Said casing has a lateral opening closed by a cover 67 made of an insulating material, and which cover is provided with a packing 68. The cover 67 is fastened by screws 69.

25 The hubs 64 are adjusted around the pins 61, and the pin 62 passes through the outstanding hub 65', and therein is threaded a stuffing-box nut 70, which is fastened in place by a nut and lock nut 71 holding the 30 casing 63 against the pressure of a special spring 72, wound around the bushing hubs 64 between the securing plates 73.

On the inside of the cover 67 is fastened 35 a metallic bracket 74 which holds a contact pin 75 secured by a nut and lock nut 76. Near the contact point of pin 75 there is a collar which serves as a stop for a spring 77 in such a manner that stem 75 yields to a shock; said stem is in vertical alignment 40 with the pin 62.

One of the conductors of the system is connected to the metallic bracket 74 across an opening 67' in the cover 67.

Having thus described the system and the 45 construction of the circuit breaker designed to operate same, the several steps of operation will now be explained.

Assume the case of a double track A and B where the circuit breakers are set being of 50 the type shown in Figs. 12 to 15 and also assume a train coming on track A in the direction indicated by the arrow in Fig. 2. Before the train arrives at the circuit-breaker 16, that is to say in the non-operative 55 condition of the system, a circuit is established from the positive pole of the source of electricity 2 to the magnet 5 of relay 3 and from this relay through the conductor 24 to the circuit-breaker 16, being in this special case one of those as shown in 60 Figures 12 to 15, in which the points of contact 77 and 62' are maintained separated.

Conductor line 32' provides the return of 65 the current to source 2. Another interrupted circuit is formed by the conductor 29,

the armature 12 in contact with point 14, the conductor 32, the armature 7 and the circuit is interrupted at the point 8, from which point it leads to the signals and from these signals to the negative pole of source 70 2. Separate circuits are formed to include each signal.

The above refers to circuits directly associated with relay 3. Referring to relay 4 there is established the following interrupted 75 circuit: from the positive pole of source 2 conductor 29, wire 30 which includes the magnet 11 and branch lines 31 to the circuit breakers 17 and 18, the circuit being interrupted on account of the separation of contact points 62' and 74, and the circuit through the rails 37 and line 32' to negative 80 pole of source 2.

Under these conditions and supposing that 85 a train is passing over the circuit-breaker 16, it presses the casing 63, overcoming the resistance of the springs 72, and the contact point of pin 77 comes in contact with the point 62' of pin 62. And the circuit which is passing through conductor 24 excites magnet 5 which attracts armature 7 against contact point 8. The magnet 6 connected to the latter point will be excited due to the circuit which is passing from the positive pole of source 2 through the conductor 29 90 to the armature 12, which is in contact with point 14; from this point the current passes through the conductor 32 to the armature 7 and contact point 8 closing the conductor the circuit 33' and operating the signal-circuits 95 from point 8 through the conductors 25, 26 and 27 which leads to each signal, the signal circuits being closed through the corresponding conductors of each signal which connect the same with the negative pole of 100 source 2.

From the above explanation it can be understood that after the train passes beyond the circuit-breaker 16, the signals continue 110 to operate because the circuit formed by magnet 6, point 8, each signal conductor, and conductor 33', continues closed, notwithstanding the separation of contact points of the circuit-breakers.

The train going on its way reaches the 115 circuit-breaker 17 which, as is illustrated in Fig. 1 is installed in the proper danger-zone, for instance on the level crossing C.

The contact points 77 and 62' of the above 120 circuit-breaker comes in contact and a circuit formed by conductor 29 tap 30, circuit-breaker 17, the rail itself, and line 32' is established, the magnet 11 will be excited attracting armature 12 overcoming the resistance of spring 15, and then the circuit 125 established by the point 8 and the signals, is broken, the magnet 6, being demagnetized, stops the signal when the train has passed beyond circuit-breaker 17 and the circuit of magnet 11 is broken. The armature 12 will 130

then be drawn by spring 15 and the circuit which passes through the armature and point 14 through conductor 32 is opened at point 9, which will be in contact with the 6 spring contact 7.

Assuming that a train is coming on the next track B in the direction indicated by the arrow in Fig. 3, when the train passes over the circuit-breaker 19, a circuit is established, the circuit passing through the conductor 24, to the magnet 5 and through the tap 44' to the circuit breaker 19 and from same to the corresponding rail returning through line 32' and magnet 5 which will 10 attract the armature 7 against the contact 8 and operating the signal-circuit in the same manner as explained before.

The train continuing will operate the closing of the circuit formed by the conductor 29 from the positive pole of source 2, and which conductor passes across the winding of magnet 11, and through the tapped wire 30 is connected to the branch line 31 which connects both circuit-breakers, and through 25 the rails and line 32' returning to the negative pole of the source, the armature 12 will be attracted against the contact point of magnet 11, causing the signal to cease, which will be understood from the previous explanation.

A common case that may happen in the practice will be a single track on which are operated trains going and coming. In this case it is necessary to make a suitable installation to obtain best results in the working 35 of the system, requiring five circuit-breakers in the track having conductor 30 with three branches, one applied to the circuit-breaker in the crossing, and the others applied to circuit breaker on either side 40 thereof. The conductor 24 will be connected with two intermediate circuit-breakers on either side of the circuit-breakers in the crossing. The above explanation refers 45 to a case in which a train travels in either direction; when the train passes over the first circuit-breaker the magnet 11 will be excited, but the working of the signal will not occur. When the train passes over the 50 circuit-breaker which operates magnet 5 the signal will be operated, but when the train passes over the circuit-breaker in the crossing the signals cease. In going on its way the train passing over the contact of 55 magnet 5 will again operate the signals, but when it reaches the next circuit-breaker which is connected to magnet 11, the signals cease.

It must be borne in mind that the distance between the two circuit-breakers installed on either side of the crossing will be so short that the successive steps of operation will be almost simultaneous.

Various other installations may be possible according to the requirements of the

case, especially when the system is used for another purpose, which is not especially applied to railways, but to highways, roads, etc.

Having explained clearly the operation of this system, and referring especially to the signals of same, it is shown in the drawing that the tower 1 has in its top a signal, consisting of a light, whose rays pass through the glasses placed on the four sides of the 75 tower; it is obvious that the glasses on the road-side should be red and the ones on the railroad-side should be green. The candle-power of the light should be sufficient so that it can be seen at a proper distance. The sounding signal would a suitable electric gong or bell 80, or a whistle, or other apparatus or device, which produces a sound 80 that can be heard at a suitable distance.

Finally in Fig. 16 is shown a typical construction of a signal to be visible during the day, to the mechanism of which I do not wish to limit myself but only to illustrate a preferred construction to be used in connection with the system. Said mechanism consists of a shaft 81, one of its ends constituting the case for a solenoid coil 82 connected to the respective conductor 25 of the system. The opposite end of the shaft 81 passes between horizontal rollers loosely mounted in 95 the upper part 84' of an angular support 84 in whose horizontal part is a stop 85 against which shaft 81 is drawn by the tension of a spring 86 fastened therein and to a pin 87.

The shaft 81 is connected to an arm 93 in the face end of which a signal 94 is written in the form of a word of warning, and also a signal 95 on which is designed a symbol used in railroad traffic. The axle 81' is rocked through a connection by a link 91 ending in its joint with the axle 81 in an integral collar 71' and which link has in its lower part a slot which gives ample play for a trunnion 92 which projects laterally from 105 axle 81. The collar 91' has a notch 91" in which is engaged a ratchet pawl 90" having a stop member 90 which bears over an inclined offset 81' at the shaft 81, and which member 90 is pivoted in 90' to an arm 88 fastened to the upper part 84' of the support 110 115 120 125 130 135 140 145 150 155 160 165 170 175 180 185 190 195 198 200 205 210 215 220 225 230 235 240 245 250 255 260 265 270 275 280 285 290 nected from the notch 91" in the collar 91' and the shaft 93 rocks 90°; then the signals 94 and 95 come to the position shown in dotted line in Fig. 16, the signal 94 being 5 visible from the highway and the signal 95 being invisible from the railroad line.

When the circuit is broken the solenoid coil 82 is demagnetized and the shaft 81 under the tension of the spring 86 turns to its 10 former position and the offset 81' forces the stop 90 to its former engagement position in the groove 91".

While my invention has been described with reference to the details of construction 15 of certain elements, it is not intended thereby, in any manner, to limit the invention, as it is clear that the same may be employed in other construction and in other relations and may be subject to numerous modifications, apparent to those skilled in the art, all 20 of which comes within the spirit and scope of my invention.

What I claim and desire to secure by Letters Patent of the United States is:

25 A signal system including a source of electrical energy and a signal, two relays, one having two solenoids, the other, a single solenoid, an armature for each relay, the armature of the single relay being normally in 30 closed circuit relation between one pole of said source and the armature of said double relay, the latter armature being normally in open circuit position, a contact with which the armature of the double relay cooperates, 35 said contact being in electrical connection by parallel paths with the other pole of said source, said signal being intercalated in one path, and one of the solenoids of said double

relay in the other path, a train-actuated normally open circuit closer in circuit with the 40 first mentioned pole of said electrical source, the other solenoid of said double relay being intercalated in this circuit, said circuit closer being actuatable by a train to close its circuit, energizing said second mentioned solenoid of the double relay to draw the armature of said double relay to circuit-closing position, energizing simultaneously said signal and the first mentioned solenoid of said double relay, and a second normally open 45 train actuated circuit closer in circuit with said source and the solenoid of the single relay, positioned to be successively actuated subsequent to the opening of said first mentioned train actuated circuit closer for closing the circuit through said solenoid of the single relay, drawing the armature of said last mentioned solenoid to open circuit position, breaking the circuit through the armature and first mentioned solenoid of the 50 double relay, thus restoring the armature of said double relay to open circuit position, the first mentioned solenoid of the double relay holding the armature of said double relay in closed circuit position during the 55 interim between opening of the first train actuated circuit closer and the closing of the second train actuated circuit closer, after the second mentioned solenoid of said double relay has been de-energized through the opening of the first mentioned train actuated circuit closer.

In testimony whereof I have signed my name to this specification.

SERGIO J VASSALLO y VALLADARES.
